FIREARM

Leon A. Rix, Ilion, N. Y., assignor to Remington Arms Company, Inc., Bridgeport, Conn., a corporation of Delaware

Application May 23, 1944, Serial No. 536,876

3 Claims. (Cl. 42—75)

1

The present invention relates to firearms, and particularly to firearms of the magazine type wherein a plurality of shot shells are carried in a magazine tube for automatic feeding to the receiver. In firearms of this type the magazine tube is secured in the forward end of the receiver and is carried in the fore-end piece which abuts the forward end of the receiver. The forward end of the magazine tube is closed by a magazine cap which constitutes a forward abutment for the fore-end, the fore-end being channeled to receive the lower end of the barrel which carries a lug encircling the magazine tube and pressed forwardly against an abutment shoulder of the fore-end by means of a recoil spring, also encircling the magazine tube. Upon firing, the barrel recoils relatively to the fore-end and the receiver to perform the operations incident to ejecting a fired shell and reloading. After completion of the recoil movement of the barrel it is thrust forward by the spring and the shock of the impact of the lug with the abutment shoulder of the fore-end is transmitted to the fore-end and the parts of the firearm associated therewith. As the magazine cap is opposed to the recoil shock in the fore-end it is apt to jar loose or turn after repeated firing. Also barrel expansion from the heat of repeated firing may affect the relative fit between the parts and cause looseness. It is an object of the present invention to provide an effective locking means for preventing the magazine cap from jarring loose or turning, while at the same time permitting it to be readily adjusted to take up looseness or to be removed for the purpose of assembling or disassembling the fore-end.

A further object is to provide a magazine cap structure which may be engaged with any desired degree of tightness, and is effectually locked against jarring loose or turning in any position of adjustment.

Another object of the invention is to provide a magazine cap structure of relatively simple and economical manufacture, permitting it to be quantity produced by modern manufacturing methods, while still maintaining extremely accurate fit and cooperation between its parts.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a fragmentary longitudinal side ele-

vation, partly in section, of a firearm embodying the invention.

Fig. 2 is a fragmentary view, partly in side elevation and partly in vertical section, and on an enlarged scale, showing the magazine cap structure of the invention and the contiguous parts of the firearm associated therewith.

Fig. 3 is a vertical transverse sectional view, taken along the line 3—3 of Fig. 2.

10 Fig. 4 is a horizontal sectional view, taken along the line 4—4 of Fig. 2.

Fig. 5 is a detail inner end elevation of the magazine cap element, removed from the firearm.

15 Fig. 6 is a detail forward end elevation of the magazine cap element, removed from the firearm.

Similar reference characters indicate corresponding parts throughout the several figures of the drawing.

Referring to the drawing, the firearm illustrated by way of example, and in which the invention is embodied, is of the automatic repeating type and comprises a barrel 10, a receiver 11, and a fore-end 12, the rearward end of the fore-end abutting the forward end of the receiver 11 and 20 preferably being provided with a tenon 13 seated in a recess 14 in the receiver, as shown clearly in Fig. 1. Rigidly secured to the barrel 10 is an apertured lug 15 which encircles the forward end of the magazine tube 16, the latter being secured 25 at its rearward end in the receiver and extending in longitudinal relation through a channeled recess 17 in the fore-end and having its forward end engaged in a cylindrical passage 18 in the forward part of the fore-end, this passage terminating at its rearward end at a shoulder 19 of the fore-end against which the apertured lug 15 is normally engaged. A recoil spring 20 is engaged about the magazine tube 16 and is compressed between the forward end of the receiver 40 and a friction collar 21 slidable upon the magazine tube and normally pressed forwardly against the apertured lug 15 by the recoil spring. Upon firing the gun the barrel 10 recoils with respect to the receiver, the magazine tube and the fore-end, 45 the apertured lug 15 moving rearwardly with the recoil end compressing the spring 20, which, at the end of the recoil movement, returns the barrel to its normal position. The recoil spring necessarily having considerable power, the lug 15 is 50 brought against the shoulder 19 with very substantial force and the shock of stopping the barrel is transmitted to the fore-end where it is opposed by the magazine cap secured in the forward end of the magazine tube, and presently to 55 be more fully described.

Within the forward end of the magazine tube 16, which is substantially flush with the forward end surface of the fore-end 12, there is engaged a bushing 22, fixedly secured therein by brazing or other suitable methods, and provided with an internal screw thread 23. At its inner end the bushing is beveled inwardly and is provided with a circumferential series of radial tooth serrations 24 of ratcheting V-type.

Within the magazine tube there is engaged a shot shell follower 25, engaged at its forward side by the magazine spring 26 which normally exerts rearward expansive force upon the follower to press the shot shells 27 rearwardly in the magazine, this spring engaging at its forward end with a detent washer 28 seating against the inner end of the bushing 22.

The detent washer 28 is of dish form with its circumferential marginal portion beveled to conform to the inwardly beveled end of the bushing 22, and this marginal portion has pressed therein a series of ratcheting teeth 29 disposed at a corresponding angle to the teeth 24 of the bushing and meshing therewith, being firmly pressed into engagement with the end of the bushing by the expansive force of the magazine spring 26. The angularity of the V-shaped teeth is such that upon turning movement being imparted to the detent washer the teeth of the washer will ride over the teeth of the bushing, the detent washer as it is rotated from one tooth to the next moving away from the bushing against the force of the spring and reseating against the bushing under the force of the spring.

Upon the forward side of the detent washer there is provided a diametrically disposed key projection 30, preferably pressed therefrom, and adapted to cooperatively interlock with the magazine cap, as will presently more fully appear. The height of the key projection 30 is greater than the depth of the teeth 24 and 29 of the bushing and washer, for the purpose of maintaining the interlocking relation of the washer with the cap during ratcheting movement of the washer, as will presently more fully appear.

The magazine cap comprises a head 31 provided with a relatively wide seating shoulder 32 adapted to be engaged with a substantial surface of the forward end of the fore-end 12 in surrounding relation to the forward end of the magazine tube, to retain the assembled relation of the fore-end. A threaded stud 33 projects axially from the shouldered end of the head and is screwed into the internally threaded bushing 22. At its inner end the stud is provided with a diametrically disposed key slot 34, adapted to be interlockingly engaged by the key projection 30 of the detent washer. The length of the stud is predetermined so that in its fully engaged position, with the shoulder 32 abutting the forward end of the fore-end, and with the washer in fully seated meshing engagement with the inner end of the bushing 22, the inner end of the stud is slightly spaced from the forward side of the detent washer. Thus, when the cap is tightly adjusted it will not raise the detent washer out of engagement with the bushing. The depth of the slot 34 and the corresponding height of the key projection 30 are such that engagement will be maintained therebetween when the cap is not fully engaged. Thus, as the magazine cap is screwed into place it becomes interlocked with

the key projection of the detent washer, and thereupon during the completion of the engaging movement of the cap the detent washer is turned with it, the teeth of the washer ratcheting over the teeth of the bushing 22 until the cap is tightly engaged with the forward end of the fore-end. In this tightly engaged position the teeth of the washer are in fully seated meshing engagement with the teeth of the fixed bushing under the pressure of the magazine spring 26, and the cap is thus resiliently held against turning relatively to the magazine tube. In order to further tighten or to remove the cap it is simply turned in one or the other directions with sufficient force to cause the detent washer to ratchet over the end of the bushing 22.

The form of the invention illustrated in the drawing and described herein is typical and illustrative only, and it is evident that the invention is capable of embodiments in other forms, all falling within the scope of the appended claims, which are to be broadly construed.

What is claimed is:

1. In a firearm comprising a barrel, a cartridge-holding magazine associated with said barrel, a cartridge-feeding spring in said magazine, and a fore-end mounted on said magazine: means for holding said fore-end in assembled relationship with said magazine comprising a member having threaded engagement with said magazine and abutting said fore-end, an abutment associated with said magazine, a detent member urged to engage said abutment by said cartridge-feeding spring, and means associated respectively with said fore-end-holding member and said detent member for resisting relative rotation therebetween.
2. In a firearm comprising a barrel, a cartridge-holding magazine associated with said barrel, a cartridge-feeding spring in said magazine, and a fore-end mounted on said magazine: means for holding said fore-end in assembled relationship with said magazine comprising a fore-end holding member threadably engageable with the magazine, a serrated abutment within and secured to said magazine, a serrated detent member yieldingly urged into interlocking engagement with said abutment by said cartridge feeding spring, and interlocking means associated with said detent member and said fore-end holding member arranged to engage each other as said fore-end holding member is advanced to effective position.
3. In a firearm comprising a barrel, a cartridge-holding magazine associated with said barrel, a cartridge-feeding spring in said magazine, and a fore-end mounted on said magazine: means for holding said fore-end in assembled relationship with said magazine comprising an interiorly threaded collar secured within said magazine and provided with a serrated end, a serrated detent member yieldingly urged into engagement with the serrated end of said collar by said cartridge-feeding spring, a fore-end holding cap member provided with a threaded boss for engagement in said interiorly threaded collar, and lug-and-slot means associated with said boss and detent member and arranged to engage each other as said cap member is advanced to fore-end holding position.
